(57) **CLAIM**

The ornamental design for a vehicle control button, as shown and described.

DESCRIPTION

It is related to application Ser. No. 29/714,778, entitled Vehicle Control Button, filed concurrently herewith. The present application is also related to application Ser. No. 29/578,541, entitled Autonomous Vehicle Overall Interior, filed Sep. 22, 2016 and issued Sep. 5, 2017 as U.S. Design Pat. No. D796,403, which is a divisional of application Ser. No. 29/491,937, entitled Autonomous Vehicle Overall Interior, filed May 27, 2014 and issued Nov. 1, 2016 as U.S. Design Pat. No. D770,349; to application Ser. No. 29/491,870, entitled Autonomous Vehicle Storage Bin/Tray, filed May 27, 2014 and issued Dec. 8, 2015 as U.S. Design Pat. No. D744,935; to application Ser. No. 29/547,496, entitled Autonomous Vehicle Seat, filed Dec. 4, 2015 and issued Feb. 7, 2017 as U.S. Design Pat. No. D778,080, which is a divisional of application Ser. No. 29/491,868, entitled Autonomous Vehicle Seat, filed May 27, 2014 and issued May 10, 2016 as U.S. Design Pat. No. D755,531; to application Ser. No. 29/491,867, entitled Autonomous Vehicle Console, filed May 27, 2014 and issued Aug. 23, 2016 as U.S. Design Pat. No. D764,386; and to application Ser. No. 29/491,889, entitled Autonomous Vehicle Pull Over Button, filed May 27, 2014.

FIG. 1 is a top view of a vehicle control button according to a first embodiment; and,

FIG. 2 is a top view of a vehicle control button according to a second embodiment.

The portions shown in a pattern or patterns of stipple illustrate areas of contrasting appearance.
